UNITED STATES PATENT OFFICE.

FRANK HEDLEY, OF YONKERS, AND JAMES S. DOYLE, OF MOUNT VERNON, NEW YORK.

CONDUCTOR'S OR CASHIER'S COLLECTION-COUNTER FOR CARS.

1,119,509.

Specification of Letters Patent.

Patented Dec. 1, 1914.

Application filed May 7, 1913. Serial No. 765,979.

To all whom it may concern:

Be it known that we, FRANK HEDLEY and JAMES S. DOYLE, citizens of the United States, residing, respectively, at Yonkers and Mount Vernon, in the county of Westchester, State of New York, have made a certain new and useful Invention in Conductors' or Cashiers' Collection-Counters for Cars, of which the following is a specification.

This invention relates to fare collection counters or stands for conductors or cashiers on street cars, busses or the like.

The object of the invention is to provide a shiftable stand or counter for the use of cashiers or conductors on street cars while collecting or making change for fares of passengers.

The invention consists substantially in the construction, combination, location and relative arrangement of parts, all as will be more fully hereinafter set forth, as shown in the accompanying drawings, and finally pointed out in the appended claims.

In the drawings:—Figure 1 is a view in front elevation showing a counter or stand embodying our invention applied to a street car, portions of the car being broken off and parts in vertical longitudinal section. Fig. 2 is a view in vertical transverse section on the line 2, 2, Fig. 1, looking in the direction of the arrows, parts of the car floor and roof broken off. Fig. 3 is a sectional view in floor plan of a portion of a car showing the application of a counter or stand to a street car, the plane of section being indicated by line 3, 3, Fig. 1, looking in the direction of the arrows. Fig. 4 is a view in perspective showing the stand or counter in position for use, the car sides and floor being broken off.

Fig. 5 is a broken detail view, partly in section showing a floor step socket for the removable vertical fare box standard. Fig. 6 is a broken detail view in section showing the detachable seat catch or support. Fig. 7 is a broken detail view in section, showing the detachable catch for the counter or stand wicket. Figs. 8 and 9 are respectively broken detail views in front and side elevation, showing the detachable bearing for the upper end of the fare register shaft. Fig. 10 is a detail view in horizontal section on the line 10, 10 Fig. 9, looking in the direction of the arrows. Fig. 11 is a broken detail view in vertical section on the line 11, 11, Fig. 12 showing the detachable supporting

connection of the counter table with a vertical standard of the frame. Fig. 12 is a similar view in section on the line 12, 12, Fig. 11, looking in the direction of the arrows. Fig. 13 is a broken detail view in plan showing an engaging arm of the counter table with the vertical supporting standard of the fare register.

The same part is designated by the same reference numeral wherever it occurs throughout the several views.

Rapid transit street car service, particularly in the larger cities where the difficulties are constantly increasing, on account of the increase in the numbers of passengers to be handled necessitates rapidity of handling the passengers and the collection of their fares. The advent of the modern fare-prepayment cars increases the necessity for expedition in collecting the fares of boarding passengers, while economy and efficiency of operation require the conductors or cashiers on the cars to be able to perform the duties of making change and receiving, depositing and registering fares and transfers with ease and facility. At the same time the station of the conductor or cashier, while performing the duty of making change or collecting, registering and depositing fares should be so arranged as not to interfere with or be disturbed by the proper movement of passengers while entering or leaving the car.

It is among the special purposes of our present invention to provide a stand or counter for the use of conductors or cashiers on street cars in the performance of their duties in this regard, and in carrying out our invention we propose to employ a stand or counter of general arrangement similar to the gates or windows of banks or cashier's desks of business institutions, and to adopt this arrangement for use on street cars we propose to make the same detachable and shiftable so as to be located at the proper position and in the proper relation with reference to the entrance or exit doorway of the car, and we also propose to employ the same in connection with proper passage forming barriers or railings to facilitate the proper movement of the passengers while boarding and alighting from the car without undue interference.

While we have shown our invention as applied to a street car of the center entrance type, it is to be understood that in its

broadest scope, as defined in the claims, our invention is not to be limited or restricted in respect to the particular type of car in connection with which it is to be employed.

5 In the particular type of car shown doorways are provided in the sides of the car opposite each other, and, as shown, these doorways are located intermediate the ends of the car, and are controlled by doors 10, 10 11. It is obvious that any suitable or desired type of door may be employed. We have shown doors of the sliding type as 15 illustrative examples, said doors being each composed of panels which coincidentally slide in opposite directions with reference to each other, and when moved to open position they are received in pockets 12, 13, formed in the sides of the car.

Opposite each side of each doorway is located a standard 14, which is secured at its lower end to the floor of the car at a point approximately one third the transverse width of the car, the corresponding standards 14, on opposite sides of the car being in 20 line with each other transversely of the car and spaced apart sufficiently to afford a passageway indicated at 15, Fig. 3, between them, at the longitudinal center of the car to accommodate passengers in passing into 25 or from the seating spaces of the car, on one or both sides of the doorways, according to the location of the doorways. The upper ends of the standards 14, are turned outwardly and extend horizontally, as shown at 30 16, to the sides of the car, approximately breast high from the floor of the car. Extending vertically from each horizontal portion 16, of said standards, is another standard section 17, which is secured at its upper end to the ceiling of the car. Each pair of these standards forms a passageway between them which extends part way transversely across the car from the corresponding side doorway. At a point about the 35 midwidth of each of these passageways are located vertical standards 18, 19, in line with each other transversely of the car floor, which are secured to the floor of the car, the inner standards 18, extending to the ceiling of the car, while the outermost standard 19, which is located in proximity to the doorway has its upper end turned inwardly and horizontally, approximately breast high from the level of the floor as indicated at 20, 40 secured to the standard 18. The standards 18, 19 serve to divide the space between the associated standards 14 opposite each doorway into separate passages, one of which, if desired, may be used by entering passengers 45 and the other by alighting passengers, or both of which may be used for both boarding and alighting passengers, when the cashier's or conductor's stand is located on the opposite side of the car, as will more 50 fully appear hereinafter.

We will now describe a cashier's or conductor's stand or counter associated with a car landing arrangement such as above described. It will be understood, however, that the stand or counter arrangement is 70 shiftable from one side of the car to the other so as to be on the opposite side of the car from the doorway which is in use for boarding and alighting passengers, and, in accordance with our invention, and in order 75 to take up a minimum space, we propose to locate the stand or counter, when in position for use, in one or the other of the transverse passageways formed by the standards 14, 18 and 19. 80

In its essential features the cashier's or conductor's stand or counter includes a wicker or lattice frame 21, having a horizontal table or counter shelf 22 and a window opening 23, through the wicker or lattice frame through which passengers pay their fares or present their money to the conductor or cashier for the purpose of making change, the cashier or conductor being located behind the wicker or lattice frame, 85 and between the same and the adjacent car door which is maintained closed. The latticed frame is detachably and removably supported on the standards 17 and 18, and the horizontal portion 20 of the standard 19. 90 A simple arrangement for this purpose is shown wherein a bracket 24, see Figs. 3, 11 and 12, is secured to the underside of the table or counter shelf 22, at the side edge thereof, which bracket is provided with a 100 forked end with downturned fingers 25, which are seated in a groove 26, formed in a collar 27, mounted on the standard 17. At its other side edge, the table or counter shelf 22 has secured to its underside a bracket 28, 105 see Fig. 13, which is provided with a hook-shaped extension 29, arranged to partially encircle or engage around a vertical standard 30, which is employed in connection with a fare register device 31, presently to be referred to more at length. By lifting the lattice frame 21 and its table or shelf 22, so as to free the bracket fingers 25, from the groove 26 of collar 27, and then slightly shifting the same to free the member 29 110 from its engagement with the standard 30, said frame and table may be readily detached for removal to the opposite side of the car when desired or required. A detachable and removable side frame 32, may 115 also be provided to still further inclose the space occupied by the cashier or conductor. This side frame is provided with upper and lower strap portions 33, 34, which embrace the standard 30, the lower strap portion 34, serving as a support for the hook member 29 of the cashier's or conductor's table. An arm 35 is pivotally mounted on the upper edge of the side frame 32, and is provided with a hook member 36 which, when said 120 125 130

arm is swung down into horizontal position engages the standard 18, see Figs. 4 and 7. The arm 35, is also provided with a notch 37 in the edge thereof which engages over a pin 38 carried by the side frame 32, thereby forming a detachable locking device for said side frame. In order to still further secure the side frame in place, while still retaining its detachability, a laterally swinging arm 39 is pivotally connected to the lower edge of the side frame and is provided with a hooked end 40 adapted to engage over or partially around the horizontal portion 20 of standard 19. By releasing the arms 35 and 40 the side frame and standard 30 may be readily detached and removed for use on the opposite side of the car whenever required.

While a fare register is not essential to our invention we have shown such a device as being carried at the upper end of standard 30, and where such a device is employed we make suitable provision for detachably carrying the upper end thereof. In the particular arrangement we have shown to illustrate our invention, a bracket 41, is secured to the ceiling of the car, and this bracket is provided with a forked extension 42, between the forked portions of which the upper end of the spindle 43 of the register device is received. A pivoted spring pressed locking dog 44, serves to retain the spindle in place. By swinging the dog out of retaining relation the spindle 43 may be readily and easily removed from the forked extension 42. When the fare register is in place it is obvious that it may be operated in any suitable or well known way.

While the use of a fare box is not essential to our invention we have shown such a device at 45, and which may be of any suitable, convenient or well known type. In the arrangement shown the fare box is carried upon a vertical standard 46, which is removably stepped at its lower end into a seat or socket 47, formed in the floor of the car to receive the same. It will be understood that a standard socket or seat 47 is provided in the floor of the car at whatever point it is desired to locate the fare box. A convenient location therefor is shown adjacent to the standard 18, but somewhat nearer the center line of the car and in all events in convenient position with relation to the conductor or cashier.

If desired a detachable and removable seat for the cashier or conductor is provided behind the table or counter and its associated lattice frame, such a seat is shown at 48, and which is or may be hinged or otherwise suitably supported at one end to one of the side standards 14, 16. In practice we hinge the seats 48 to panels carried by the standards 14, 16 and when the seat is not required for use it is simply swung down out of the way

as shown in Fig. 3. At its other end the seat 48 is provided with a slideable spring pressed catch 49, which detachably engages over a cross bar 50, secured between standards 18, 19. By this construction the seat 48, for the conductor or cashier may be easily and quickly arranged in position for use or removed from such position. In order that the cashier or conductor while occupying the proper position behind the counter or desk for the performance of the required duties of such position may be elevated somewhat so as to be able to see over the heads of passengers and to observe their boarding and alighting movements and so as to be the better able to control the movements of the doors, we prefer to locate the seat 48 above the normal height of the car seats and in that case it may be desirable to provide a foot rest for the cashier or conductor. Such a device may be in the form of a plate or step 51, which is hinged or supported and arranged in all respects similar to the seat 48.

It is obvious that the doors 10, 11, may be operated in any suitable, convenient, or well known manner and by any usual or well known form of mechanism, and controlled in any well known manner from any convenient point. But these details form no part of our present invention.

Having now set forth the object and nature of our invention, and a construction and arrangement embodying the principles thereof, what we claim as new and useful and of our own invention and desire to secure by Letters Patent is:—

1. A street car having doorways opposite each other in the sides thereof, and a shiftable cashier's desk or counter, and means for detachably supporting the same adjacent either of said doorways. 105

2. A street car having a doorway, barriers located at the doorway to divide the space adjacent thereto into passageways, a cashier's or conductor's desk or counter and means for detachably supporting the same upon said barriers. 110

3. A street car having doorways opposite each other in the sides thereof, barriers arranged adjacent each doorway to divide the space inside the same into passages, a desk or counter, and means for detachably supporting the same on either of said barriers. 115

4. A street car having doorways opposite each other in the sides thereof, transversely extending barriers at the sides of each doorway, a transversely extending auxiliary barrier intermediate each side barrier, and a desk or counter detachably mounted on a side and intermediate barrier of one of said doorways. 125

5. A street car having doorways opposite each other in the sides thereof, barriers located at the sides and opposite the center 130

- of each doorway, a desk or counter and means for detachably mounting the same upon the side and center barrier of either of said doorways.
6. A street car having a doorway, standards arranged at the side of the car opposite said doorway, a desk or table and means for detachably mounting the same upon said standards.
10. 7. A street car having a doorway, standards located at the side of the car opposite said doorway, a desk or table and a seat therefor, and means for detachably mounting said desk or counter and seat upon said standards.
15. 8. A street car having doorways opposite each other in the sides thereof, standards associated with each doorway, a wicket frame having a table and window and

means for detachably supporting said frame 20 upon either set of standards.

9. A street car having doorways opposite each other in the sides thereof, standards associated with each doorway, a desk or counter, means for detachably supporting 25 said desk or counter upon either set of standards, and a fare box associated with said counter or desk.

In testimony whereof we have hereunto set 30 our hands in the presence of the subscribing witnesses, on this 22nd day of April A. D. 1913.

FRANK HEDLEY.
JAMES S. DOYLE.
